George Mueller ^{Inventor}

By Attorney

UNITED STATES PATENT OFFICE.

GEORGE MUELLER, OF SALT LAKE CITY, UTAH.

OVEN TRUCK.

1,417,096.

Specification of Letters Patent. Patented May 23, 1922.

Original application filed August 23, 1920, Serial No. 405,362. Divided and this application filed August 23, 1920. Serial No. 405,364.

To all whom it may concern:

Be it known that I, GEORGE MUELLER, a citizen of the United States, residing at Salt Lake City, in the county of Salt Lake and State of Utah, have invented new and useful Improvements in an Oven Truck, of which the following is a specification.

The invention relates to an oven truck and is a division of an application filed by me on the 23rd day of August, 1920, Serial No. 405,362.

The object of the present invention is to provide a simple, practical and comparatively inexpensive oven truck of strong, and durable construction equipped with rails and adapted to carry a tray for enabling the tray to be readily run into and out of the oven whereby the entire batch for baking may be quickly placed in the oven at one time and rapidly removed therefrom without material loss of heat.

A further object of the invention is to provide an oven truck of this character adapted to be readily guided and removed from one point or place to another for use in connection with one or more ovens and equipped with means for adjusting the rails for arranging the same either at an inclination or a horizontal position and at the proper elevation to couple accurately with the rails of the furnace.

A further object of the invention is to provide adjusting means located centrally of one end of the oven truck and at opposite sides of the other end thereof and capable of independent adjustment and also of simultaneous adjustment of the means at one end of the truck whereby the rails may be quickly positioned with perfect accuracy.

With these and other objects in view, the invention consists in the construction and novel combination of parts hereinafter fully described, illustrated in the accompanying drawings and pointed out in the claims here-
45 to appended, it being understood that various changes in the form, proportion, size and minor details of construction, within the scope of the appended claims, may be resorted to without departing from the spirit 50 of the invention or sacrificing any of the advantages thereof.

In the accompanying drawings, in which like numerals of reference designate corresponding parts in the several figures:—

Figure 1 is a side elevation of an oven truck constructed in accordance with this invention and shown connected to a baker's oven, the latter being in section.

Figure 2 is an end elevation of the oven truck partly in section.

Figure 3 is a plan view of the same.

Figure 4 is an enlarged detail sectional view illustrating the construction for coupling the rails of the oven truck to the oven rails.

Figure 5 is a side elevation of the same, the rails being separated.

Figure 6 is a detail view illustrating the arrangement of the beveled gearing for connecting the side adjusting screws.

Figure 7 is a detail view illustrating the slidable connection between the bevel gearing and the side adjusting screws.

Figure 8 is a detail view illustrating the device for holding the adjusting nuts of the side adjusting screws stationary while the screws are simultaneously adjusted by the connecting gearing.

In the accompanying drawings in which the oven truck 10 is shown connected to a baker's oven, 1 designates the baking chamber provided at opposite sides with narrow grooves or channels 2 for the reception of rails 3 constructed and arranged as described in the aforesaid application and adapted to receive the wheels 5 of a wheeled pan carrying tray or carriage 6 of the oven truck 10 to enable the tray or carriage to be readily run into and out of the oven. The rails 3 which are inverted T-shaped are arranged in 90 channeled casings or housings 4 and the said rails 3 and the channeled casings or housings 4 are provided at the front of the oven with extensions 7 and 8 which project beyond the oven and which are adapted to have 95 connected to them rails 9 of the oven truck 10. The rails 9 of the oven truck are inverted T-shaped and the terminal portions of the webs are cut away at the top at 11 to provide recesses to receive upper projecting portions 12 of the extensions 7 of the rails 3. The extensions 7 are cut away at

the base at 13 to receive the projecting base portion 14 of the rails 9. The said extensions 7 are also provided with side plates 15 riveted or otherwise secured to the side 5 faces of the webs of the extensions 7 and having outer spaced parallel portions 16 and outer terminal diverging guiding portions 17 adapted to guide the rails of the oven truck into the narrow spaces between the 10 parallel portions 16 of the side plates 15. The parallel portions 16 and the webs of the oven truck rails 9 are provided with registering perforations 18 and 19 adapted to receive suitable fastening means for coupling 15 the rails of the oven truck to be securely fastened to the oven rails. By this construction, the truck is rigidly connected to the oven rails and constitutes practically a portion of the oven in the handling of the 20 wheeled tray or carriage and after a tray or carriage has been introduced into an oven the truck may be transferred to another oven or left in position for the removal of the tray or carriage as desired. It has been 25 found in practice that a wheeled tray or carriage, containing between 200 and 250 loaves, will require only about one-half of a minute for introducing it into the baking chamber and that less time is required for 30 the removal of the tray or carriage.

The oven is provided with an automatically closing counter-balanced door 20 hinged at the top at 21 and provided with a projecting weighted arm 22 adapted to 35 partly counter-balance the door 20 and enable an easy operation of the same. The wheels of the tray or carriage are preferably ball bearing but any anti-friction wheels or 40 wheels of any other construction may of course be employed and the said tray comprises an open receptacle frame composed of side bars 27 and connecting end bars 28 and having adjustable pan supporting bars 29 mounted upon the said side bars and extending entirely across the frame of the tray. 45 The pan supporting bars 29 which are preferably inverted T-shaped, are secured in their adjustments by adjusting and locking strips or members 31 arranged horizontally at opposite sides of the wheeled tray or carriage and having notches or recesses 32 for engaging the webs of the pan supporting bars as described in a co-pending application filed on the 23rd day of August 1920, Serial 50 No. 405,363.

The adjusting bars or members are detachably secured to the frame or carriage by bolts 33 or other suitable fastening means. Any suitable means may of course 60 be employed for enabling the strips or members 31 to be detachably secured to the side bars of the tray or carriage and the arrangement of the pans may be reversed if desired as the bars 29 can extend longitudinally as 65 well as transversely of the tray or carriage,

The pans 34 which are spaced apart, are connected in sets by end bars 35, and they are spaced apart to permit the end bars to rest upon the upper edges of the vertical portions of the T-shaped supporting bars 70 29. The pans are hung from the supporting bars and are arranged so that when the tray is run into the furnace, the bottoms of the pans will just clear the floor of the oven, one-quarter to one-half of an inch clearance 75 being sufficient and the arranging of the pans in such close relation with the floor of the oven will subject the contents of the pans to the entire heat of the oven floor with practically the same heating effect as when the pans 80 are placed directly upon the floor of the oven. The wheels of the tray or carriage are preferably flanged as shown to form grooves to receive the rails of the oven truck and oven and they may be mounted in any suitable 85 brackets or supports 36. No claim is made, in the present application, to the particular construction of the wheeled oven tray or carriage as this forms the subject matter of the 90 said application Serial No. 405,363. 90

The pans 34 may be of any desired construction and the supporting bars 29 are also adapted to receive biscuit or bread trays 39 having a wire mesh bottom and adapted for the baking of biscuits rolls, or 95 the like. The wire mesh bottoms will enable the contents of the biscuit or bread trays to bake as quickly as if they were lying directly upon the bottom or floor of the baking chamber. The wire mesh biscuit or bread 100 pan or tray forms the subject matter of a separate divisional application, Serial No. 473,360½ and is constructed as shown and described therein.

The rails 9 of the oven truck are preferably connected by transverse angle bars 37 and the said rails 9 are provided with pivoted stops 48 preferably consisting of approximately L-shaped plates or members pivoted at their angles at 49 and having upwardly 110 extending arms or portions 50 for engaging the brackets or other portions of the wheeled tray or carriage to retain the same on the oven truck. The stop plates or pivoted stops 48 also have inwardly extending arms 51 115 provided with perforations 52 adapted to receive pins or bolts 52' which also cooperate with openings in the track 9 for securing the pivoted stops in the full line position shown in the drawings. When the pins or 120 bolts 52 are removed, the pivoted stops 48 are adapted to be swung downwardly to the dotted line position for removing the wheeled tray or carriage from the oven truck.

The angle bars 37 have spaced parallel 125 depending wings or flanges between which are mounted blocks 53 and 54 provided in their lower faces with sockets 55 for the reception of double and single adjusting screws 56 and 57 respectively mounted on 130

the truck frame 58 and located respectfully at opposite sides of one end of the same and centrally of the other end thereof as clearly shown in the drawings. The double adjusting screws 56 which are mounted in suitable brackets 59, are engaged by adjustable nuts 60 having hand wheels 61 for rotating them and suitably mounted on the truck frame. The hand wheels 61, which are located at 10 the top of the truck frame are adapted for independent adjustment to enable the double adjusting screws to be separately adjusted to set the rails properly with relation to each other. The said double adjusting screws 56 are also connected by gearing hereinafter described and are provided with a hand wheel 62 for enabling the double adjusting screws 56 to be simultaneously operated for adjusting the rails of the oven 15 truck to arrange them properly with relation to the rails of the bakers oven. The lower portions of the double adjusting screws 56 are provided with keys or feathers 63 which operate in suitable key-ways of 20 horizontal bevel pinions 64 which mesh with vertical bevel pinions 65 of a transverse shaft 66 journaled in suitable bearings of the oven truck frame and extending across the same to arrange the gears 65 in proper 25 position to mesh with the gears 64 of the double adjusting screws 56.

The adjustable nuts 60 are provided with suitable locking means for holding them against rotary movement after independent 30 adjustment so that they will operate as fixed nuts in the simultaneous adjustment of the screws 56. The single adjusting screw 57 engages a fixed nut 67 and is mounted in suitable brackets 68 and is provided with a 35 hand wheel 69 for adjusting the said screw 57. By adjusting the screws, the track formed by the rails of the oven truck may be arranged either in a horizontal position or at an inclination and also in elevation in 40 the range of the adjustment of the screws. The weight upon the screws will be ample 45 to resist upward movement of the nuts 60 in the adjustment of the latter. Also the independent adjustment of the double adjusting screws will enable the track to be adjusted 50 transversely and in the independent and simultaneous adjustment of the double adjusting screws, the central arrangement of the single adjusting screw and the socket 55 connecting the same with the superimposed track, will permit the vertical and lateral tilting of the track.

The truck frame is mounted at one end upon side wheels 70 and at the other end 60 upon a caster wheel 71. The side wheels are connected by an axle 72 and the caster wheel 71 is in a pivoted bracket 73 or other suitable support to permit the wheel 71 to function as a caster wheel in the handling 65 of the oven truck. A base 74 is provided

at the center of the caster wheel end of the frame for the mounting of the caster wheel bracket or support.

The device for holding the hand wheel or nut 60 stationary while the side screws 70 56 are simultaneously adjusted comprises a cog wheel 75 preferably formed integral with the end wheel 60 but it may be connected with the end wheel in any other desired manner. The cog wheel is provided at intervals with oppositely beveled recesses 76 75 adapted to be engaged by inwardly extending teeth 77 of side levers 78 pivoted at one end at 79 to a suitable supporting bar or member 80 and connected intermediate of 80 their ends by a coiled spring 81 which urges the ratchet levers 78 inwardly and maintains the same in engagement with the cog or ratchet wheel 75. The free portions of the levers 78 are preferably supported upon 85 a transverse member 82 but the levers may be mounted in any other desired manner as may be readily understood. The teeth or engaging portions 77 of the levers are oppositely beveled to fit the notches of the cog 90 or ratchet wheel and they engage the cog or ratchet wheel with a sufficient gripping action to hold the same stationary during the simultaneous adjustment of the side screws and at the same time they will permit an independent adjustment or rotary movement 95 of the end wheels 61 and the side screws when power is applied to the said end wheel 61 with sufficient force to rotate the same.

What is claimed is:—

1. An oven truck comprising a frame provided at one end with a single centrally arranged adjusting screw and having at the other end spaced double adjusting screws, a fixed nut mounted on the frame and engaging the single adjusting screw, an adjustable nut mounted on the frame and provided with operating means engaging the double adjusting screws, gearing connecting the double adjusting screws, means for rotating the double adjusting screws, and a tray carrying frame mounted upon and supported by the said screws and adapted to be arranged either in a horizontal or inclined position.

2. An oven truck including a frame, a single adjusting screw located at one end of the frame and provided with operating means, a fixed nut mounted on the frame and engaging the single adjusting screw, double adjusting screws mounted on the frame at the other end thereof, adjusting nuts mounted on the frame and engaging the double adjusting screws, means for locking the adjustable nuts against rotary movement, and means for simultaneously rotating the double adjusting screws.

3. An oven truck including a frame, a single adjusting screw located at one end of the frame and provided with operating

100

105

110

115

120

125

130

means, a fixed nut mounted on the frame and engaging the single adjusting screw, double adjusting screws mounted on the frame at the other end thereof, adjusting nuts mounted on the frame and engaging the double adjusting screws, means for locking the adjustable nuts against rotary movement, gearing connecting the double adjusting screws for simultaneously rotation, and 10 an operating device for rotating the double adjusting screws.

4. An oven truck comprising a frame, a single adjusting screw mounted on the frame centrally of one end thereof, double 15 adjusting screws mounted on the frame at opposite sides of the other end thereof, means for adjusting the double adjusting screws simultaneously and independently, and a tray carrying frame provided with 20 central and side sockets receiving the single and double adjusting screws.

5. An oven truck comprising a frame, a single adjusting screw mounted on the frame centrally of one end thereof, double adjusting screws mounted on the frame at opposite sides of the other end thereof, means for adjusting the double adjusting screws simultaneously and independently a tray carrying 25 frame provided with central and side sockets 30 receiving the single and double adjusting

screws, side adjusting wheels located at the end of the frame adjacent the double adjusting screws, and a centrally arranged caster wheel supporting the frame below the single adjusting screw.

35

6. An oven truck including a truck frame, an adjustable superimposed track carrying frame comprising rails, spaced connecting bars arranged in pairs and central and side blocks secured between the connecting bars 40 and provided with sockets, center and side adjusting screws mounted on the truck frame and arranged at opposite side of one end of the truck and at the center of the other end thereof and fitting in the screws and means 45 for adjusting the screws.

7. An oven truck including a truck frame an adjustable superimposed track carrying frame comprising rails, spaced connecting bars arranged in pairs and central and side 50 blocks secured between the connecting bars and provided with sockets, center and side adjusting screws mounted on the truck frame and fitting in the screws, and means for adjusting the screws independently and for 55 also adjusting the side screws simultaneously.

In witness whereof, I have hereunto affixed my signature.

GEORGE MUELLER.
